Symmes, Lechner & Lechner

UNITED STATES PATENT OFFICE.

STANLEY A. JACQUES, OF CHICAGO, ILLINOIS, ASSIGNEE TO INTERNATIONAL COMBUSTION ENGINEERING CORPORATION, A CORPORATION OF DELAWARE.

BURNER.

Application filed November 4, 1925. Serial No. 66,699.

This invention relates to burners and is particularly useful in the burning of pulverized coal although it can also be used to advantage in the burning of gas or any other fuel with which it is desired to secure an intimate mixture of fuel and air at the burner and it is the primary object of my invention to provide a burner which will accomplish this result.

Another object of my invention is the provision of a burner wherein the fuel is divided into comparatively thin sheets and combustion air is supplied between the sheets of fuel, the parts being so arranged that the two will become thoroughly mixed within a comparatively short distance of the burner.

A further object of my invention is the provision of a burner of the character described composed of end sections and intermediate sections one or more of which may be secured between the end sections to form a sectional burner of any desired size.

These objects, together with such others as may appear hereinafter, or are incident to the invention, I obtain by means of a construction which I have illustrated in preferred form in the accompanying drawings, wherein

Fig. 1 is a side elevation, partially in section of a burner assembly;

Fig. 2 is an end elevation of the burner shown in Fig. 1.

The burner illustrated comprises the three top sections 1 which are identical in construction, the end sections 2, which are also identical, and the intermediate sections 3, which are likewise identical.

The top sections 1 are of somewhat "fish-tail" shape viewed from the side, as in Fig. 1 and flare slightly viewed from the end, as in Fig. 2. These top sections are provided at their upper edges with flanges 4 to which a fuel supply pipe can be secured. The lower edge of each of these top sections 1 is also provided with a flange 5 along each side thereof to which the lower sections 2 and 3 are secured by means of the flanges 6 and the bolts 7 passing therethrough.

The intermediate sections 3 are composed of rectangular side members 8-8 with the flanges 6 at their upper edges. Secured to these side members 8 and extending between them are the hollow dividing plates 9. These

plates are closed at their upper edge in the form of an inverted V as shown at 10 and are open along the bottom. Ports 11 through the side walls 8-8 open into the interior of the hollow plates 9, for the purpose of supplying air to the interior thereof and the deflectors 12 extend between the side plates 8-8 just beneath the opening in the bottom of the hollow plates 9 to deflect the air flowing through these plates.

The end sections 2 are similar to the sections 3 but each is provided with an end wall 13 to form the end of an assembled burner, this end wall also forming one side of one of the hollow plates. The end sections are also provided with lugs 14, on opposite sides thereof through which the bolts 15 are passed and the intermediate sections are thus held securely in position with the side 8 of one section fitting snugly against the side 8 of the adjacent section.

Near the upper part of the top member 1 and extending across the opening into which the fuel flows are the deflectors 16 which serve to divide the fuel stream somewhat and cause it to fall more uniformly over each of the lower sections.

It will be seen that in the assembled burner the hollow dividing plates 9 form slots 17 for the passage of the fuel therebetween.

The operation of this burner is as follows: A mixture of coal and air from a feeder or mill enters the burner at the top. Here it meets the deflectors 16 which break up the stream to distribute it evenly throughout the chambers. The coal and air mixture thus enters the slots 17. Air supplied through the ports 11 enters the hollow plates and upon emerging from the bottom thereof is deflected into the path of the fuel and air falling therethrough. The ports 11 are of a size to admit the proper amount of additional air needed at the burner and by virtue of my improved construction this air is brought into intimate contact with the thin sheets of fuel descending through the slots and the air so admitted becomes intimately mixed with the fuel a short distance from the burner.

If desired, the ports 11 can be made sufficiently large to supply enough air in addition to that entering with the fuel to complete combustion. However, if desired, the ports can be made smaller and further air

to complete combustion supplied through the walls of the furnace in a manner well known in the art.

It will be seen that a burner of any desired size can be constructed by the use of the counterpart members which I have shown.

What I claim is:

1. A burner for pulverized fuel and the like including a sectional casing forming a fuel passage having a fuel receiving opening and a fuel discharging opening, the receiving opening being at the top of the burner, hollow dividing plates each having an open bottom and extending transversely of the said passage intermediate the ends thereof, said plates forming slots for the passage of fuel therebetween, means for admitting air to the interior of said hollow plates and deflectors adjacent the open bottoms of the hollow dividing plates whereby the fuel passing through the said burner is mixed with air flowing through the said plates within the burner.

2. A burner for pulverized fuel and the like comprising a plurality of counterpart fishtail shaped sections, each section having a fuel receiving opening and a fuel discharging opening, the fuel receiving openings being at the top of the burner, a sectional casing providing a fuel passage for the fuel discharging from the fishtail shaped sections and having means for securing it to the fishtail shaped sections, said casing including end sections and a plurality of intermediate sections, the intermediate sections each having oppositely disposed side plates and a hollow dividing plate therebetween and the end sections forming closures for the ends of the burner, air inlets for admitting air to the interior of said hollow plates and air outlets for said hollow plates for discharging air into the fuel passing through the burner.

In testimony whereof, I have hereunto signed my name.

STANLEY A. JACQUES.
